United States Patent Office

Des. 230,251
Patented Feb. 5, 1974

230,251

DOOR HANDLE

Russell W. Waldo, St. Paul, Minn., assignor to Ideal Security Hardware Corporation, St. Paul, Minn.

Filed July 24, 1972, Ser. No. 274,413

Term of patent 14 years

Int. Cl. D8—06

U.S. Cl. D8—150

FIG. 1

FIG. 4

FIG. 2

FIG. 3

FIG. 5

FIG. 1 is a view in perspective of the door handle of this invention, as seen from one end and the inner or door facing side thereof;

FIG. 2 is a view in elevation of one end of the handle of FIG. 1, the opposite end being a mirror image of FIG. 2;

FIG. 3 is a view in outer side elevation;

FIG. 4 is a side elevation as seen from the right to the left with respect to FIG. 3; and

FIG. 5 is a view in side elevation as seen from the left to the right with respect to FIG. 3.

I claim:

The ornamental design for a door handle, as shown and described.
